UNITED STATES PATENT OFFICE.

FRANK NEWFORTH, JR., OF NORWOOD, OHIO, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

Original application filed September 18, 1914, Serial No. 862,292. Patent No. 1,256,817, dated February 19, 1918. Divided and this application filed February 4, 1918. Serial No. 215,239.

To all whom it may concern:

Be it known that I, FRANK NEWFORTH, Jr., citizen of the United States of America, and resident of Norwood, county of Hamilton, 5 Ohio, have invented certain new and useful Improvements in Automatic Telephone Systems, of which the following is a specification.

My invention relates to automatic telephone systems in general. More particularly it relates to systems in which trunk selecting apparatus is employed and in which traffic trunks are used in connection therewith. Among the special objects of my 15 invention are the following:

To provide in a measured service reverse battery telephone system a traffic line terminating in an operator's position, which operator upon responding automatically cuts off 20 the ringing current in the calling connector without operating the meter associated with the calling circuit; to provide an improved type of trunking switch; and to provide certain details and features of improvement 25 tending to increase the efficiency and serviceability of a system of the above character.

The means to accomplish the foregoing and other useful ends are hereinafter set forth and claimed.

30 In the accompanying drawings Figs. 1 and 2 taken together show a connection established between a calling automatic substation A and the lines of a called automatic substation A'.

35 In Fig. 1 there is shown the automatic substation A, line switch C, a meter X associated with the line and a first selector switch E.

In Fig. 2 there is shown a connector 40 switch H, and line switch C' of substation A'. There is also shown at J a group of relays which may be located in a manual board and are for the purpose of allowing an operator to answer an information call or the 45 like without operating the meter of the calling line as will be hereinafter more fully explained.

Figs. 3 and 4 represent in detail a portion of a so-called self aligning line switch 50 plunger, that is a line switch plunger which will at all times return to its normal posi-

tion on the controlling shaft regardless of the position of the shaft.

Fig. 5 represents in detail a portion of a master switch showing the association of 55 the line switch plungers therewith.

The automatic substation A (Fig. 1) comprises the usual receiver 2, transmitter 3, ringer 4 and condenser 5. Being an automatic substation, it is also provided with a 60 suitable impulse sending mechanism for controlling the automatic switches, which mechanism is represented diagrammatically by a pair of impulse springs 6 and 7 and an impulse wheel 8, which may be controlled 65 in a well known manner through the medium of a dial (not shown) provided with finger holes in such a way that the impulse springs may be momentarily separated a 70 number of times corresponding to the respective digits of the number of the called subscriber.

The subscriber's individual switch C is of the general type of subscriber's switch shown in British patent to R. W. James, 75 #26,301 of 1906, more closely resembling, however, the particular type shown in British patent to T. G. Martin, #1419 of 1910. This line switch comprises, among other details, a plunger 200 shown in Figs. 3, 4 and 80 5 pivotally attached to the end of a so-called plunger arm 9. The back portion of this plunger 200 is fan shaped. Pivotally mounted on this fan shape portion at the points 201 and 201^a there are two arms, 202 and 202^a.

These arms 202 and 202^a are limited in their rotation by two pins 203 and 203^a, at their outer ends they are provided with rollers 205 and 205^a which engage the flange 206 on the usual shaft 207. When the 90 plunger 200 is in normal position. The arms 202 and 202^a are held in this position by means of a spring 208, one end of which is secured to each arm. When the plunger is operated as shown in Fig. 4 the shaft 207 95 is rotated in the usual and well known manner and operates to force the arm 202^a away from the retaining pin 203^a. The arm 202 however is prevented from rotating by means of the pin 203. Thus it will be seen 100 that when the shaft 207 is rotated, at the time the plunger is in an operated position,

the spring 208 will be placed under tension and the plunger held against rotation and when the plunger is released, it operates through the medium of the arms 202 and 202^a, to bring the plunger back to its normal position, that is, until the arms 202 and 202^a engage their respective stop pins 203 and 203^a. The plunger arm 9 is controlled by a magnet 10, which comprises an operating winding 11 and a holding winding 12. This magnet also controls the cut-off armature 13. The winding 11 operates both the plunger arm 9 and armature 13, while the winding 12 is strong enough only to operate the armature 13 and to hold the plunger arm 9 in its operated position. When the plunger arm 9 is operated its plunger is forced into a bank of contact springs, forcing the springs 14, 15, 16 and 17 into engagement with the springs 18, 19, 20 and 21, respectively. Although only one set of springs 14-21, is shown, each line switch is provided with a plurality of such sets, each set forming the terminal of a trunk line leading to a first selector switch E. Each trunk line is connected in multiple to the corresponding springs of all the line switches of the group which is controlled by the master switch D. The switch C is controlled by the subscriber through the medium of the line relay 22, which relay is preferably slow acting, that is, slow to release its armature upon deenergizing. This relay instead of being connected directly to battery as is usually the case is connected to battery through the springs 60, 61 controlled by the plunger arm 9. The purpose of connecting relay 9 in this manner will be hereinafter pointed out.

The master switch D is of the general type of master switches shown in British Patents #26 301 of 1906, and 1419 of 1910. The function of the master switch, as is well known, is to maintain the plungers of all the idle line switches in position to engage the terminals of an idle trunk line. Referring to Fig. 5, the master switch D consists essentially of a motor magnet 354 which operates the ratchet wheel 355, a bank of contacts comprising a number of individual segments a and one common segment 356, a busy trunk relay 357, and a locking relay 358. The wiper 359 is adapted to always keep some one of the individual segments in an electrical connection with the common segment 356. By means of a suitable mechanical connection the rotary motion of the ratchet wheel 355 is transmitted to the plunger shaft to give said shaft a reciprocating motion to move the idle plungers back and forth in front of the bank contacts. To the plunger shaft there is also secured a cam 360 having in its surface a number of circular openings which are engaged by the pin 361 on the

armature 362. The openings in the cam 360 are so spaced that the pin 361 can engage an opening only when the plungers that are in locking engagement with the plunger shaft are directly in front of a trunk terminal.

Associated with the line A there is shown a call register 28, which is controlled by a double wound magnet 29. The windings of the magnet 29 are so proportioned that it requires the energization of both windings in the same direction to attract the armature, said armature being unaffected by the energization of either winding alone, or by the energization of the two windings in opposition to each other.

The first selector switch E is of the general type of selector switches disclosed in U. S. Letters Patent to Keith, Erickson and Erickson, #815,321, granted March 13, 1906. Among other details, the selector E comprises a bank of contacts arranged in horizontal rows or levels, which are adapted to be engaged by a set of wipers 30, 31 and 32 carried upon a shaft (not shown), which has a vertical movement controlled by the vertical magnet 33 and a rotary motion controlled by the rotary magnet 34. The operations of the switch are controlled through the medium of the double wound line relay 35. Means for permitting the switch to be restored to normal position are provided in the release magnet 36, which, upon energizing, withdraws the retaining pawls from the shaft. The spring contacts 37 and 38 are permitted to close only when the switch shaft has been raised one or more steps from its lowest position. The relays 39 and 40 are slow acting relays, that is, relays which de-energize slowly after their energizing circuits are broken. This slow action is usually obtained by placing a ring of copper around one end of the core of the relay.

The connector shown at H (Fig. 2) is of the general type of connector switch disclosed in U. S. Letters Patent to Keith, Erickson and Erickson, #815,176, the circuits, however, being modified to adapt the switch to operate in a system in which the central office apparatus is controlled by impulses delivered over the two sides of the line in series. Like the selectors, the connector is provided with a shaft (not shown), carrying the wipers 41, 42 and 43, and which is controlled by the vertical magnet 44 and rotary magnet 45. The usual side switch comprising the wipers 46, 47, 48 and 49 is controlled by the private magnet 50 in the usual and well known manner. Magnet 53 is the usual release magnet. The line relay 51 is connected with the line through the reversing springs of a so-called back bridge relay 52, through the windings of which latter relay the called line is provided

with talking current. The ringer relay 253 is the means through which the application of ringing current to the called line is controlled. At Q there is shown a busy 5 signaling machine which is connected to springs of relay 55, the function of which is to send a busy tone under certain conditions back over the line. The complete 10 operation of this relay will be described later. The busy signaling machine as represented herein, comprises an induction coil or transformer, the primary winding of which is included in a local circuit with a battery and an interrupter. Through the medium 15 of this interrupter an intermittent interrupted current is supplied to the primary winding which induces an intermittent alternating current in the secondary winding whereby when said winding is connected to 20 the subscriber's line an intermittent buzzing sound is heard in the receiver.

The line switch C' is similar to the line switch C the circuits being modified, however, as will be hereinafter more fully 25 explained.

The substation A' is similar in all respects to the substation A.

For the purpose of supplying current for operating the central office apparatus and 30 for talking purposes there is shown a battery B having one terminal grounded at G.

In the event of a subscriber having his telephone removed or taken out of service for non-payment or other numerous reasons, 35 his line is disconnected from the central office apparatus and the contacts of the connector bank constituting the terminals of said subscriber's line are wired to what is known as a traffic trunk as shown at J in 40 Fig. 2, the conductors of said trunk being designated by the reference numerals 165 and 166. Therefore, upon the subscriber at substation A attempting to call a subscriber whose telephone it has been assumed 45 has been taken out of service he will signal an operator who will give him the necessary information. It is desirable that such a call be not charged to the calling substation, therefore, arrangements are provided 50 in the group of relays shown at J, Fig. 2, for the preventing of the operation of the meter of the calling substation when a call similar to that above mentioned is made.

A general description of the apparatus 55 having been given it will now be explained how a connection may be established between a calling automatic substation A and a called automatic substation A', the number of which we will assume to be 220, and also 60 how the meter is prevented from being operated when the subscriber at substation A attempts to call substation A² (not shown) whose line has been connected to the above mentioned traffic trunk. Upon the removal 65 of the receiver from the switch hook at the

calling substation preparatory to making a call, the talking circuit of the substation is bridged across the line conductors 71 and 72 by the hook switch springs 73 and 74, whereby the circuit of the line relay 22 70 of the switch C is closed. This circuit extends from ground G² through the springs 75 and 76, line 71, substation A, line 72, springs 77 and 78, relay 22, springs 60 and 61 to the battery lead 80. The relay 22, 75 upon energizing, closes the circuit of the operating winding 11, which operates to disconnect the relay 22 from the line through the medium of the armature 13 and springs 60 and 61, and to thrust the plunger of the 80 switch into the terminal of the trunk before which it is being held by the master switch, whereby the line circuit is extended through the springs 14 and 18, and 15 and 19 to an idle first selector switch E. The line relay 85 35 of the selector switch E is thereupon energized over a circuit extending from ground G³ through the lower winding of said relay, springs 82 and 82^a, thence over the heavy conductors to and through the substation A 90 and back over the other side of the line through the left hand winding of the meter magnet 29, springs 83 and 83^a and upper winding of line relay 35 to the battery lead 80. The relay 35, upon energizing, closes 95 the circuit of the relay 39, which in turn, upon energizing closes a circuit extending from ground G⁴ through the springs 85, line switch bank springs 20 and 16 and holding winding 12 to the battery lead 80. The 100 energization of this winding serves to hold the switch C in its operated position after the circuit of the winding 11 is broken by the relay 22, which de-energizes shortly after it is disconnected from the line. The energization of the relay 39 at the selector E also completes a circuit extending from ground G⁴ through springs 85, springs 20 and 16, through the right hand winding of the meter magnet 29 and the springs 61^a and 61 to the 110 battery lead 80. The current in this winding is in opposition to the current flowing through the line winding, and the magnet is, therefore, not operated at this time. At the same time, a guarding potential is extended 115 from ground G⁴ at the selector via conductor 80^a to the connector private bank contact of the calling line in the bank of each of the connector switches which have access thereto.

The springs 60 and 61 disengage immediately upon the operating of the plunger arm 9 which prevents the circuit of the line relay 22 from again being closed until the plunger arm 9 is again restored to normal position in front of an idle terminal. 120

Upon the closure of the springs 17 and 21 by the operation of the switch C, the master switch D operates in a well known manner to advance the plungers of the idle line switches to a position opposite an idle trunk line. 130

The calling subscriber now operates his calling device for the first digit 2 of the called number, whereby the substation impulse springs 6 and 7 are separated twice momentarily, each time breaking the circuit of the selector line relay 35. The relay 39 of the selector, being slow acting, does not deenergize during the momentary interruptions of its circuit by the relay 35, and consequently 10 each time the latter relay deenergizes an impulse is transmitted over the circuit extending from ground G⁵ through the springs 88 and 89, 90 and 91, relay 40, vertical magnet 33 and side switch wiper 62 to the battery lead 80. The vertical magnet receives two 15 impulses over this circuit and operates to raise the switch shaft and wipers two steps to a position opposite the second row or level of bank contacts, and at the same time the shaft controlled contacts 37 and 38 are closed. The slow acting relay 40 is maintained in its energized position continuously while impulses are being transmitted to the vertical magnet through it, and in its energized position 20 closes a circuit from ground G⁶ through the springs 94 and 93 and private magnet 95 to the battery lead 80. The relay 40, upon deenergizing, opens the circuit of the private magnet 95, which in turn, deenergizes and 25 allows the side switch to pass from first to second position. The wiper 62, upon passing from first to second position, closes an energizing circuit for the rotary magnet 34. This circuit extends from ground G⁷ through 30 interrupter springs 97 and 98, rotary magnet 34, wiper 62 to battery B. The rotary magnet, upon energizing, operates to rotate the shaft and shaft wipers one step onto the first bank contact of the level in which the trunk 35 lines leading to a connector H terminate. The rotary magnet upon energizing operates to break its own circuit at the interrupter springs 97 and 98 and to again close the circuit of the private magnet. The circuit for 40 the private magnet extends from ground G⁷ through springs 99 and 100, and the private magnet 95 to battery B. If the first trunk line leading from the second level of bank contacts of the selector E is in use, the private 45 wiper 32 will find the first private bank contacts supplied with a guarding ground potential, a circuit will then be closed through the private magnet 95 after the rotary magnet deenergizes, extending from said ground at the private wiper through the side switch wiper 63 (in second position), and then through magnet 95 to battery. The side switch is thus held in second position and the rotary magnet upon deenergizing 50 again closes its own circuit at springs 97 and 98 and operates to step the shaft wipers to the next bank contacts. If the next contacts are also busy the operation will be repeated, the rotary magnet operating in a manner 55 similar to that of a buzzer to rotate the shaft wipers onto bank contacts connected to an idle trunk line, at which time the private magnet deenergizes and allows the side switch to pass from second to third position. The wiper 62, upon passing to third position 60 shifts the battery connection from the rotary magnet 34 to the line switching relay 102, thus closing a circuit through the relay 102. This circuit extends from ground G⁴ through springs 85, relay 102 and wiper 62 to battery B. A circuit also extends from springs 85 through wiper 63 (in third position) to the private wiper 32. The relay 102, upon energizing, operates to disconnect the line relay 35 from the line and to connect the calling line through to the line relay 51 of the connector H, and also operates to open the circuit of the release magnet 36 at springs 103 and 104. The line relay, upon being disconnected from the line deenergizes and allows the relay 39 to deenergize. The relay 39, being slow acting, does not fall back however, until a ground has been supplied to the release trunk conductor 140 by the relay 160 of the connector switch H as will be later more 65 fully explained. The line relay 51 of the connector thereupon becomes energized and closes the circuit of the relay 160. The relay 160, upon energizing, provides a holding circuit for the line switching relay 102 of the selector switch E, and for the hold in winding 12 of the line switch C. The circuit for the line switching relay 102 extends from ground G³¹ through the springs 123, conductor 140, wiper 32, side switch wiper 63, relay 102 and the side switch wiper 62 to battery B. The circuit for the hold in winding 12 extends over the above traced circuit to side switch wiper 63, thence through bank contacts 20 and 16 and the said hold in winding to battery B. When the substation calling device is operated for the digit 2, the circuit of the connector line relay 51 is broken twice. Since the relay 160 is slow acting, it does not deenergize during the momentary interruptions of its circuit by the relay 51, so that each time the latter relay is deenergized a circuit is closed extending from ground G¹¹ through the springs 162 and 162^a, springs 163 and 163^a, relay 164, vertical magnet 44 and side switch wiper 49 to the battery lead 80. The vertical magnet 44 receives two impulses over this circuit and operates to raise the switch shaft wipers 41, 42, and 43 to a position opposite the second level of bank contacts. The relay 164, which is included in series with the vertical magnet, remains in its energized position during the entire time impulses are being transmitted through it and operates to close the circuit of the private magnet 50. After the last impulse is delivered the relay 164 opens the circuit of the private magnet 50, which upon 130

deenergizing, permits the side switch to advance from first to second position. The movement of the side switch wiper 49 from first to second position transfers the battery connection from the vertical magnet 44 to the rotary magnet 45. The calling subscriber now operates his calling device for the last digit 0 in response to which the connector line relay 51 operates to transmit ten impulses through the rotary magnet 45, in series with the relay 164, whereby the shaft wipers are rotated onto the contacts of the desired line. The relay 164 operates in response to this digit in the same manner as for the previous digit, to cause the private magnet 50 to advance the side switch one more position, that is, from second to third position after the last impulse for the digit is transmitted. By the engagement of the side switch wipers 46 and 47 with their third position contact points the line connection is finally completed to the called number.

I will first give a description of the operations that take place, assuming that connection was established to the called telephone in which case the wipers 41, 42 and 43 would be in engagement with conductors 167, 168 and 169 respectively. The circuit of the relay 170 of the called party's line switch is closed by the side switch wiper 48 passing to third position, said circuit extending from ground G^{12} through side switch wiper 48, private wiper 43, conductor 169 and through the relay 170 to battery. The connection of ground G^{12} with the connector private bank contact of the called line over the portion of the circuit just traced provides said contact with a guarding potential to prevent the busy line from being connected with by other connector switches. By the engagement of the side switch wiper 49 with its third position contact point the circuit of the ringing relay 253 is closed, which circuit extends from ground G^{12} , through the interrupter 171, relay 253, springs 172 and side switch wiper 49 to the battery B. The ringing relay 253, upon energizing, disconnects the calling from the called line and bridges the ringing current generator M across the called line to signal the called subscriber. The ringing relay is energized only intermittently through the medium of the interrupter 171. Upon the response of the called subscriber his line is provided with talking current through the windings of the back bridge relay 52 of the connector switch, which relay upon energizing, closes the circuit of the ringer cut-out relay 174. This circuit extends from ground G^{12} through the wiper 48, springs 175, and the said relay 174 to battery B. The relay 174, upon energizing, opens the circuit of the ringing relay 253 at the springs 172 and closes a locking circuit for itself through its own springs 176 independent of the springs of the back

bridge relay 52. A further result of the energization of the relay 52, upon the response of the called subscriber, is the transposition of the connection between the windings of the line relay 51 and trunk conductors 138 and 139, whereby the direction of current in the calling line is reversed. This reversal of the current in the left hand winding of the subscriber's meter relay 29 (Fig. 1) causes the two windings to assist one another to operate the meter to register the call.

After the conversation is completed the connection is released by the hanging up of the receiver at the calling substation in the following manner: When the receiver at the substation A is restored to the switch hook, the separation of the hook switch springs 73 and 74 destroys the energizing circuit of the line relay 51 (Fig. 2). The relay 51, thereupon deenergizes, and opens the circuit of the relay 160. The relay 160, upon deenergizing, opens the holding circuits of the relay 102, of the switch E and of the hold in winding 12 of line switch C and at the same time closes the circuit of the release magnet 53 of the connector H. The latter circuit extends from ground G^{11} through the springs 162 and 162^a, springs 163 and 122, shaft controlled springs 178 and the said release magnet 53 to the battery B. The magnet 53, upon energizing, restores the connector switch shaft and side switch to normal position, and its own circuit is interrupted at the springs 178 when the shaft reaches its lowest position. The deenergization of the relay 102 of the switch E serves to close the circuits of the release magnet 36. The circuit for the said magnet extends from ground G^5 through the springs 88 and 89, springs 90 and 90^a, springs 104 and 103, off normal springs 38 and 37 and the magnet 36 to battery B. When the shaft reaches its lowest position the circuit of the magnet 36 is opened by the separation of the off normal springs 38 and 37. The hold in winding 12, upon deenergizing, allows the plunger arm 9 and cut-off armature 13 to return to normal. Thus it will be seen that everything is released and in readiness for another call.

If the called line had been in use the calling subscriber would have received the busy signal in the following manner: The private wiper 43 upon coming to rest upon the private bank contact of the called line would have found said contact grounded, whereby a circuit would have been closed extending from said ground, through wiper 43, side switch wiper 48, (in second position) springs 185 and 186, relay 55, springs 188 and 187, and the private magnet 50 to battery B. The relay 55, upon operating, opens the circuit of the rotary magnet at the springs 190 and closes a locking circuit for itself extending from ground G^{11} through springs 130

- 189, springs 191 and 186, and over the circuit above traced to battery B. The engagement of springs 192 and 193 places a busy signal from the machine Q onto the calling line.
- 5 The calling subscriber, upon receiving the busy signal replaces his receiver upon the hook thereby releasing the connection in the manner similar to that hereinbefore explained.
- 10 It will now be explained how the calling subscriber can, after obtaining connection with the lines of the substation A², whose telephone has been discontinued, converse with an operator without having the call registered. As has been explained, if the service of the called substation has been discontinued, then the normal conductors of said substation will be disconnected from the telephone line and connected to the
- 15 traffic trunk 165 and 166. Thus when the connector comes to rest upon the called number, that is, when the wipers 41 and 42 come to rest on the terminals of the traffic trunk conductors 165 and 166, the relay 190^a
- 20 is bridged across the conductors 191^a and 192^a, thereby being placed in the circuit with the back bridge relay 52. The relay 190^a energizes over this circuit, but is of sufficient resistance to prevent the relay 52 from oper-
- 25 atively energizing. The relay 190^a, upon energizing, closes a circuit through the lamp 193^a. The operator, upon noting the glowing of the lamp 193^a operates the key K thereby placing the talking set across the
- 30 conductors 165 and 166 and also, due to the make before break arrangement of the springs 194, 195 and 196, sends one impulse from ground G³⁸ through the primary of the induction coil 197 to battery. This
- 35 impulse induces an impulse in the secondary of the coil 197, which is in series with the coil 198. The relay 198 is energized by this impulse and operates to momentarily short circuit the conductors 165 and 166. The
- 40 back bridge relay 52 is momentarily energized due to this short circuiting of conductors 165 and 166 and operates to close the circuit of the ringer lock-out relay 174, which, in turn operates, as has been explained to
- 45 open the circuit of the ringing relay 253, thereby disconnecting the ringing current from the line. The momentary reversal of current by the operating of relay 52, however, is not of sufficient duration to operate
- 50 the meter, thus preventing the call from being registered. The engagement of the springs 194 and 196 closes a circuit through the relay 199, which, in turn operates to break the circuit of the lamp 193^a and to
- 55 also place the coil 210 in series with the relay 190^a, this being effective to increase the impedance across the conductors 165 and 166.
- 60 The release of this connection is made in the same manner as hereinbefore explained.
- 65 The line switch shown at C' (Fig. 2) op-
- erates over a circuit slightly different from that explained for line switch C. When the receiver at substation A' is removed preparatory to making a call a circuit is closed extending from ground G¹⁹ through springs 70 211 and 212, conductor 213, thence through substation A', conductor 214, springs 215 and 216, windings 217 and 218 in series to the battery B. The current through these windings is not of sufficient strength to attract the plunger arm 222 but however, does attract the armature 219 and is sufficient to hold the plunger in its attracted position when once operated. The operation of the armature 219 closes a circuit for the coil 218 75 extending from ground G²⁰ through springs 223 and 224, which are controlled by the master switch, thence through springs 225 and 226, springs 220 and 221, and the winding 218 to battery B. The arm 222 is now 80 attracted and operates to force the plunger into the bank of contacts as described for switch C, separates the springs 225 and 226 and causes the engagement of springs 227 and 228. The separating of contact springs 90 225 and 226 disconnects the ground from winding 218. The engagement of springs 227 and 228 again places the windings 217 and 218 in series, over a circuit extending from the ground at the release trunk conductor 229 through springs 227 and 228 and the said windings 217 and 218 to battery B, thereby retaining the arm 222 in an operated position. It will be seen that when the plunger arm breaks the contact of springs 100 225 and 226, thereby disconnecting ground G²⁰ from the winding 218, the plunger is held in its operated position by the original energizing circuit from ground G¹⁹ over the substation line and through the windings 105 218 and 217 in series to battery B until the release relay of the selector has time to energize and connect ground to conductor 169. The energization of the relay 170 disconnects the windings 217 and 218, and ground 110 G¹⁹ from the line. The relay 170, being slow acting, prevents the line switch from again immediately operating until the plunger has had time to return to normal position after the calling subscriber has released.
- 115 It will thus be seen that I have provided an improved automatic telephone system of the measured service common battery type in which the meter is operated by the reversal of the current when the called subscriber answers. With this improved form of system a discontinued subscriber at the central office can be connected with a traffic trunk associated with an operator and the operator can answer and thereby cut off the ringing 120 current at the connector without permitting the current of the calling side of the line to be reversed for a sufficient length of time to operate the meter. It will be noted that when a call is extended to a traffic trunk or 125

trouble operator, the momentary reversal and restoration of the current in the calling line will give a double click or signal in the calling subscriber's receiver in place of the 5 customary single click which occurs when the call is extended to called subscriber. The calling man may be instructed to note this signal and hang up in case the double signal is received.

10 I have further provided an improved form of self aligning trunking switch which enables a subscriber to release a connection and immediately remove his receiver without causing the switch to establish a connection with a busy trunk.

Furthermore I provide an improved form of self aligning plunger type switch in which the plunger is always in engagement with the plunger shaft regardless of whether 20 the plunger is holding the line in engagement with a trunk or not and which is more positive and efficient in its action.

While I have illustrated my invention in connection with a special or particular type 25 of apparatus and circuits, I do not wish to be limited to the exact structure shown and described.

What I claim as my invention is:

1. In a telephone system, a calling and 30 a called subscriber's line, means for establishing a connection between said lines, a meter for said calling line, means for automatically applying ringing current to the called line, means for automatically disconnecting said ringing current from the called line and for operating said calling line meter when connection has been established 35 with the called line, a traffic trunk terminating in an operator's board, means for establishing connection from said calling line to said traffic trunk and for automatically applying ringing current thereto, and means controlled by the response of the operator for automatically disconnecting 40 the ringing current from the traffic trunk without operating said calling meter.

2. In a telephone system, a plurality of 50 subscribers' lines, an automatic connector switch provided with bank contacts in which a plurality of said lines terminate, a traffic trunk connected with certain of said bank contacts, means for extending connection from one of said lines to said connector, means for then operating said 55 connector to establish a connection with another of said subscribers' lines, means in said connector for automatically applying ringing current to said called line, a meter on the calling line, means controlled by the 60 response of the called subscriber for automatically disconnecting the ringing current from the called line and for operating the meter, means for operating said connector to establish connection with said traffic 65 trunk and applying ringing current thereto,

an operator's set adapted to be connected with said trunk, and means controlled upon the response of said operator for disconnecting said ringing current from the trunk without operating said meter. 70

3. In a telephone system, a line, a meter in said line, an automatic connector switch connected with said line and provided with bank contacts, a plurality of subscribers' lines connected with certain of said contacts, 75 a traffic trunk connected with other of said contacts, an operator's set adapted to be connected with said traffic trunk, a source of ringing current, means for automatically connecting said ringing current with said contacts when said connector establishes connection therewith, a relay in said connector, means for causing a continuous flow of current through said relay to energize the same when connection is made with a 85 subscriber's line and said subscriber responds to operate the meter, means for energizing said relay only momentarily upon the response of the operator when connection is established with the traffic trunk, 90 and means controlled by the momentary energization of said relay for disconnecting the ringing current from said contacts without operating the meter.

4. In a telephone system, a subscriber's 95 line, a trunk line, a connector switch accessible to said line for connecting with said trunk line, automatic ringing equipment in said connector switch, a measured service device associated with said subscriber's line, 100 a device in said connector for preventing the operation of said equipment, said devices having different time constants, a relay in said connector for operating said devices, and means for closing a bridge across the 105 said trunk line to operate said relay in said connector, said means also for opening said bridge before said measured service device has operated.

5. In a telephone system, a subscriber's 110 line, a trunk line, a connector switch accessible to said line for connecting with said trunk line, automatic ringing equipment in said connector switch, a meter associated with said subscriber's line, a relay in said 115 connector for preventing the operation of said equipment, said relay operating more rapidly than said meter, a second relay in said connector for operating said meter and for initiating the operation of said first 120 relay, and means for closing a bridge across said trunk line to operate said second relay, said means also for opening said bridge to deenergize said second relay before said meter has operated. 125

6. In a telephone system, the combination with a calling subscriber's line and a measured service device associated therewith, of a trunk line leading to an operator's position, a link circuit for connecting 130

- said line and trunk line, automatic ringing equipment associated with said link circuit, a relay associated with said link for preventing the operation of said ringing equipment, a second relay associated with said link for operating said device and for initiating the operation of said first relay, said first relay adjusted to operate more quickly than said device, and means for closing a bridge across said trunk line to operate said second relay, said means also for opening said bridge to deenergize said second relay before said device has operated.
7. In a telephone system, the combination with a subscriber's line and a measured service device associated therewith, of a trunk line, a connector switch, means for operating said switch over said subscriber's line to connect with said trunk line, a source of ringing current, a relay in said connector for applying said source to said trunk line when connection is established therewith, a second relay in said connector for operating said device and for preventing the operation of said first relay, and means in said trunk line for closing a bridge across the same to operate said second relay, said means also for opening said bridge before said device has operated.
8. In a telephone system, a calling and a called subscriber's line, means for establishing a connection between said lines, a meter for said calling line, means for automatically applying ringing current to the called line, means for automatically disconnecting said ringing current from the called line and for operating said calling line meter when connection has been established with the called line, a traffic trunk terminating in an operator's board, said first means also for establishing connection from said calling line to said traffic trunk and for automatically applying ringing current thereto, and means for disconnecting the ringing current from the traffic trunk without operating said calling meter.
9. In a telephone system, a plurality of subscribers' lines, an automatic connector switch provided with bank contacts in which a plurality of said lines terminate, a traffic trunk connected with certain of said bank contacts, means for extending connection from one of said lines to said connector, means for then operating said connector to establish a connection with another of said subscribers' lines, means in said connector for automatically applying ringing current to said called line, a meter on the calling line, means controlled by the response of the called subscriber for automatically disconnecting the ringing current from the called line and for operating the meter, means for operating said connector to establish connection with said traffic trunk and apply ringing current thereto, an operator's set adapted to be connected with said trunk, and means for disconnecting the ringing current from the traffic trunk without operating said calling meter.
10. In a telephone system, an automatic connector switch, a line with which said switch is adapted to make connection, a relay in said switch, a second relay bridged across said line and adapted to be connected in series with said first relay when said connector establishes connection with said line, said second relay being of high resistance to prevent energization of said first relay, a trunk terminating in said connector switch, a meter associated with said trunk, means for short circuiting said high resistance relay to thereby cause the operation of said first relay, and means for automatically preventing said first relay from operating said meter.
11. In a telephone system, an automatic connector switch, a line with which said switch is adapted to make connection, a relay in said switch, a second relay bridged across said line and adapted to be connected in series with said first relay when said connector establishes connection with said line, said second relay being of high resistance to prevent energization of said first relay, a trunk line extending to said connector switch, a meter associated with said trunk, means for short circuiting said high resistance relay to thereby cause the operation of said first relay, means for applying ringing current to said line when connection is established therewith, and means controlled by the energization of said first relay for disconnecting said ringing current from the line and for preventing the operation of said meter.
12. In a telephone system, an automatic connector switch, a line with which said switch is adapted to make connection, a relay in said switch, a second relay bridged across said line and adapted to be connected in series with said first relay when said connector establishes connection with said line, said second relay being of high resistance to prevent energization of said first relay, means for short circuiting said high resistance relay to thereby cause the operation of said first relay, means for automatically connecting ringing current to said line when connection is established therewith, a trunk line extending to said switch, a meter associated with said trunk line, means controlled by the energization of said first relay for disconnecting said ringing current from the line and for reversing the current in said trunk, and means for preventing the reversal of said current from operating said meter.
13. In an automatic telephone system, an automatic connector switch provided with bank terminals, means for operating said connector to establish connection with one

- of said terminals or for establishing connection with another of said terminals, a trunk line extending to said connector switch, a meter operable over said trunk, a 5 relay in said connector, automatic means for holding said relay energized while the connector maintains connection with the first one of said terminals to reverse the current in the trunk line for operating said meter, 10 and means for only momentarily energizing said relay to prevent the operation of said meter while the connector maintains connection with the second one of said terminals.
14. In a telephone system, an automatic connector switch provided with sets of bank contacts, a plurality of subscribers' lines connected with certain of said contact sets, a traffic trunk connected with another of said 20 contact sets, an operator's telephone set adapted to be connected with said traffic trunk, a source of ringing current, means for automatically connecting said ringing current with any contact set when said connector establishes connection therewith, a trunk terminating in said connector, a meter associated with said trunk, a relay in said connector, means effective if a subscriber's line is called for holding said relay energized while the subscribers are talking for 30 operating said meter, and means responsive to the connection of said operator's set in case a connection is extended to said traffic trunk for only momentarily energizing said 35 relay to prevent the operation of said meter and yet disconnect the ringing current from the associated contacts.
15. In a telephone system, an automatic connector switch, a line with which said 40 switch is adapted to make connection, a relay in said switch, a second relay bridged across said line and adapted to be connected in series with said first relay when said connector establishes connection with said line, 45 said second relay being of high resistance to prevent energization of said first relay, a trunk terminating in said connector switch, an electromagnetic meter associated with said trunk, means for short circuiting said 50 high resistance relay to thereby cause the operation of said first relay, and means for preventing said first relay from operating said electromagnetic meter.
16. In a telephone system, an automatic 55 connector switch, a trunk line terminating in said switch, an electromagnetic meter associated with said trunk line, a line with which said switch is adapted to make connection, a relay in said switch, a second relay bridged 60 across said line and adapted to be connected in series with said first relay when said connector establishes connection with said line, said second relay being of high resistance to prevent energization of said first relay
- when the two are connected in series, a third 65 relay controlling a short-circuit about said second relay, and means for transmitting an induced impulse through said third relay to thereby cause said third relay to momentarily short circuit said second relay to 70 thereby cause only the momentary operation of said first relay to prevent the operation of said electromagnetic meter.
17. In a telephone system, the combination with lines, switches, charging apparatus for lines when calling, and means adapted to operate said apparatus when calling lines are connected by said switches to lines called for, of automatically operating means for disabling the apparatus operating means 80 when calling lines are connected by said switches to certain of said lines.
18. In a telephone system, the combination with lines, an automatic connector, charging apparatus for lines when calling, 85 and means adapted to operate said apparatus when calling lines are connected by said connector to lines called for, of automatically operating means for disabling the apparatus operating means when calling 90 lines are connected by the said connector to certain of said lines.
19. In a telephone system, an automatic connector switch, lines of two kinds accessible to said switch, a calling line and means 95 for extending it to said switch, a toll assessing device for said calling line, means for operating said switch to connect with any one of said first lines, means for operating said device if connection is established with 100 a line of one kind, and means for preventing the operation of said device if connection is established with a line of the other kind.
20. In a telephone system, an automatic 105 connector switch, lines of two kinds accessible to said switch, a calling line provided with a toll assessing device, means for extending the calling line to said switch, means for operating said switch to connect 110 with any one of said first lines, and means for operating said device effective only when a particular kind of line is called.
21. In a telephone system, a calling line provided with a registering device, a connector switch, a plurality of other lines accessible to said switch, means for extending the calling line to said switch, means for operating said switch to connect with any one of said other lines, means for operating 120 said register when the called subscriber answers, and means for rendering said last means ineffective when a particular line is called.

Signed by me at Norwood, county of 125 Hamilton, State of Ohio, this 21st day of January, 1918.

FRANK NEWFORTH, Jr.
